UNITED STATES PATENT OFFICE.

CECIL P. CAULKINS, OF NEW LONDON, CONNECTICUT.

THIMBLE.

Application filed April 28, 1926. Serial No. 105,057.

This invention relates to certain new and useful improvements in thimbles and its object is to provide a simple device for facilitating hand sewing through heavy materials.

More specifically, its object is to provide a thimble which may be used in the ordinary manner for pushing a needle and which may also be used for pulling the needle. To this end I have provided on the side of a thimble of usual form, a needle gripping device which comprises a pair of fixed lugs so shaped and relatively positioned that they may be placed over opposite sides of a needle and be made to engage or be disconnected from the needle by a simple movement of the finger. The desired result is attained without the use of any springs or movable parts such as have been suggested heretofore.

These and other objects will appear in the following specification in which a thimble which embodies the invention will be described and its novel features pointed out in claims.

Referring to the drawings in which like characters of reference designate corresponding parts in the several views.

Fig. 1 is a perspective view of one of my novel thimbles on a hand, illustrating the manner in which it is used;

Fig. 2 is an elevation on a larger scale, of the thimble shown in Fig. 1;

Fig. 3 is a similar elevation at right angles to the view shown in Fig. 2;

Fig. 4 is a sectional elevation taken on the line 4—4 of Fig. 2; and

Fig. 5 is a sectional plan view, the section being taken on line 5—5 of Fig. 2.

The thimble comprises the usual body portion 10 with at least a part of its outer surface roughened as at 11, and a rim or fillet 12.

20 is an upper lug which extends downwardly from the rim 12 and which forms a beveled lip 21 overhanging the outer surface of the body 10. 22 is a lower lug projecting from the body 10 at a point offset from the lug 20 and forming a beveled lip

23 which overhangs the outer surface of the body 10. The lips 21 and 23 are parallel and at an oblique angle to the axis of the thimble, and are oppositely beveled.

When sewing heavy material such as sail cloth, the needle may be pushed into the cloth, but it is difficult to pull it through.

When this device is used the needle is pushed part way through the cloth and as it is held between the thimble and thumb it is pushed or slid along the thimble by the thumb over the lower lug 22 and into the space between the lugs. The thumb is then moved along the needle slightly in advance of the lugs and a sufficient pressure is exerted on the side of the needle to tend to tilt the needle in relation to the lugs, thereby wedging the needle into the beveled overhanging lips of the lugs. Thus in an easy and natural position of the fingers and thumb, the needle is securely gripped by the thimble so that it may be pulled through the cloth. This tilting movement at the same time makes the thimble engage the finger more firmly and enables the operator to pull the needle with considerable force. After the needle is through the cloth and the pull on it is released, it is free to adjust its position relative to the lips 21, 23 and will release itself. Thus the operation of sewing is greatly facilitated.

The lugs are small and not unsightly nor in the way when not used, so this construction in no way interferes with the ordinary use of the thimble with such light material that the gripping device is not needed.

The angle of the lips shown in the drawings is that provided for right hand users and it is to be understood that this angle should be inclined in the opposite direction for left handed people.

What I claim is:

1. A thimble having a body and a pair of spaced rigid lugs having parallel lips overhanging the outer surface of the body and arranged to engage a needle.

2. A thimble having a body and a pair of spaced lugs having oppositely beveled parallel lips overhanging the outer surface of the body and arranged to engage a needle.

3. A thimble having a body of circular cross-section and a pair of spaced lugs having oppositely beveled parallel lips inclined to the axis of the body overhanging the outer surface of the body and arranged to engage a needle.

4. A thimble having a body of circular cross-section and a pair of spaced rigid lugs relatively offset, having oppositely beveled parallel lips inclined to the axis of the body overhanging the outer surface of the body and arranged to engage a needle.

5. A thimble having an open-ended body,

a pair of spaced rigid lugs near the open end of the body, said lugs having parallel lips overhanging the outer surface of the body and arranged to engage a needle.

6. A thimble having an open-ended body, a pair of spaced lugs near the open end of the body, said lugs having oppositely beveled parallel lips overhanging the outer surface of the body and arranged to engage a needle.

7. A thimble having an open-ended body of circular cross-section, a pair of spaced rigid lugs relatively offset near the open end of the body, said lugs having oppositely beveled parallel lips inclined to the axis of the

body overhanging the outer surface of the body and arranged to engage a needle.

8. A thimble having an open-ended body of circular cross-section, a rim around the open end of the body projecting annularly from the outer surface of the body, an upper lug depending from said rim, a lower lug relatively offset from the upper lug, said lugs having oppositely beveled parallel lips inclined to the axis of the body, overhanging the outer surface of the body and arranged to engage a needle. 20 25

In witness whereof, I have hereunto set my hand this 12 day of April, 1926.

CECIL P. CAULKINS.
